BOTTLE CLEANING APPARATUS

George J. Meyer, Milwaukee, Wis., assignor to
 Geo. J. Meyer Manufacturing Company, Cud-
 ahy, Wis., a corporation of Wisconsin

Application May 31, 1932, Serial No. 614,359

4 Claims. (Cl. 141—7)

The invention relates to apparatus for the interior cleaning of bottles.

Bottles which are to be cleaned occasionally contain loose foreign substances, such as corks, 8 cigar stubs, and paper. These substances tend to remain in the bottles during the brushing and rinsing operations, even when the bottles are in their customary inverted position, and are spun around by the brushes, usually remaining above 10 the brushes, so that the brushes will not remove them.

In order to remove these foreign substances from a bottle and to clean the interior surface 15 of the bottle, it is an object of the invention to provide an injection tube which is adapted to enter the bottle for discharging a cleaning fluid therein, and which is formed with a toothed exterior engageable with the foreign substances to urge them out of the bottle as the tube is withdrawn.

The invention further consists in the several features hereinafter set forth and more particularly defined by the annexed claims.

In the accompanying drawing, Fig. 1 is a sectional elevation of a bottle cleaning apparatus embodying the invention, an injection tube thereof being inserted into a bottle, and

Fig. 2 is a fragmentary sectional elevation of the apparatus showing the tube on its withdrawal stroke.

In this drawing, the numeral 10 designates the traveling conveyor of a bottle washing machine. The conveyor includes bottle-holding pockets 11 and is of the well-known side chain type in which the pockets are arranged in transversely extending rows, and in which the chains are provided with supporting rollers 12. The pockets 11 are adapted to receive bottles 13 therein, one being shown, and in that flight of the conveyor illustrated the bottles are supported in inverted position in the pockets.

An upwardly projecting injection tube 14 is adapted to enter the inverted bottle and is supported at its lower end on a hollow manifold 15 which carries a number of similar tubes, as shown. The tube enters the manifold from above and is clamped thereto between a collar 16 and a screw 17, the latter being threaded into the tube from below. A slot 18 formed in the tube provides communication with the interior space of the manifold. The upper end of the tube carries a cap 19 provided with inclined nozzle openings 20 through which jets of a cleaning or rinsing fluid, such as water or a solution, are forced into the

the manifold 15. The jets may also have a tangential direction with respect to the tube.

Suitable crosshead means, such as that shown in United States Patent Nos. 1,429,960 and 1,813,066, may be provided for reciprocating the 5 manifold to project the tube into the bottle and to withdraw it from the bottle.

The outer surface of the tube 14 is provided with numerous projections or teeth, here indicated to be formed by a sharp-edged buttress 10 thread 21, the shoulders thereof facing downwardly.

Any loose foreign articles, such as corks, cigar 15 stubs, and papers, in the inverted bottle fall toward the neck portion thereof, a cork 22 being indicated in the drawing as representative of the foreign articles. The cork becomes wedged between the side wall of the bottle and the serrated tube, and when the tube is withdrawn the cork is drawn downwardly, being deformed or mutilated as it is pulled out of the bottle neck. Any 20 foreign articles tending to adhere to the interior surface of the bottle will be flushed toward the neck portion by the injected liquid, and any small fragments torn from the articles will be flushed 25 out of the bottle. If the withdrawal of the article from the bottle meets with excessive resistance, the movement of the injection tube may be stopped by suitable slip joint connections 30 commonly used in various parts of bottle washing machines.

What I claim as new and desire to secure by Letters Patent is:

1. A bottle cleaning device comprising a fluid 35 injection tube of a size adapted to enter a bottle from below and having an injection opening and a rigid toothed outer portion lower than said opening for drawing a cork or other foreign article from the bottle, and means communicating with the lower end of the tube for supplying fluid thereto.

2. A bottle cleaning device comprising a substantially rigid fluid injection tube of a size adapted 45 to enter a bottle from below and having a rigid toothed outer portion for wedging a cork or other foreign article in the bottle between said portion and the inner surface of the bottle and for withdrawing said article by the relative separating movement of said tube and bottle, and means 50 communicating with the lower end of the tube for supplying fluid thereto.

3. A bottle cleaning device comprising a substantially rigid fluid injection tube of a size adapted 55 to enter a bottle from below and having a

broken outer surface forming shoulders about the tube for wedging a foreign article in the bottle between said surface and the inner surface of the bottle while the article is in any one of various positions around said tube, and for withdrawing said article from the bottle by the relative separating movement of said tube and bottle.

4. A bottle cleaning device comprising a substantially rigid fluid injection tube adapted to

enter a bottle from below and having encircling ribs presenting sharp-edged downwardly facing shoulders for wedging a foreign article in the bottle between said ribs and the inner surface of the bottle and for withdrawing said article from the bottle by the relative separating movement of said tube and bottle.

GEORGE J. MEYER.

CERTIFICATE OF CORRECTION.

Patent No. 1,987,345.

January 8, 1935.

GEORGE J. MEYER.

It is hereby certified that error appears in the printed specification of the above numbered patent requiring correction as follows: Page 1, first column, line 45, for "as" read not; and same page and column, after line 54, insert as line 55, the words bottle, the fluid passing through the tube from; and that the said Letters Patent should be read with these corrections therein that the same may conform to the record of the case in the Patent Office.

Signed and sealed this 5th day of March, A. D. 1935.

Leslie Frazer
